FISHING LURE

Charles J. Reda, 2530 Ridgewood Ave., and Arthur A. Bianchini, 1338 E. Summit St., both of Alliance, Ohio 44601

Filed Aug. 15, 1973, Ser. No. 388,384

Term of patent 14 years

Int. Cl. D22—05

U.S. Cl. D22—29

FIG. 1

FIG. 2

FIG. 4

FIG. 3

FIG. 5

FIG. 1 is a top plan view of a fishing lure embodying our new design;

FIG. 2 is a side elevational view;

FIG. 3 is a bottom view;

FIG. 4 is a front elevational view; and

FIG. 5 is a rear elevational view.

The side opposite to that shown in FIG. 2 is substantially a mirror image of FIG. 2.

We claim:

The ornamental design for a fishing lure, as shown and described.
